(57) **CLAIM**

The ornamental design for a tire pressure gauge, as shown and described.

DESCRIPTION

FIG. 1 is a front perspective view of a tire pressure gauge, showing our new design;

FIG. 2 is a rear perspective view of the embodiment shown in FIG. 1;

FIG. 3 is a bottom view of the embodiment shown in FIG. 1;

FIG. 4 is a side view of the embodiment shown in FIG. 1; FIG. 5 is a top view of the embodiment shown in FIG. 1; FIG. 6 is another side view of the embodiment shown in FIG. 1;

FIG. 7 is a front view of the embodiment shown in FIG. 1; and,

FIG. 8 is a rear view of the embodiment shown in FIG. 1. The broken lines shown are included for the purpose of illustrating portions of the tire pressure gauge that form no part of the claim.

1 Claim, 6 Drawing Sheets
